UNITED STATES PATENT OFFICE.

JOHN A. MAIER, OF LONDON, ENGLAND, ASSIGNOR TO THE ERASMIC COMPANY, LIMITED, OF WARRINGTON, ENGLAND, A CORPORATION OF GREAT BRITAIN.

DESIGN FOR A BOTTLE.

Application filed March 26, 1921. Serial No. 455,992. Term of patent 7 years.

To all whom it may concern:

Be it known that I, JOHN ARTHUR MAIER, a naturalized British subject and of 48 Fore Street, in the city of London, England, have invented a certain new, original, and ornamental Design for a Bottle, of which the following is a specification.

My new design is illustrated in the accompanying drawing, in which:

Figure 1 is a front elevation of the design; Figure 2 is a side elevation of the design; Figure 3 is a plan view of the design, and Figure 4 is a horizontal cross section of the design.

I claim:

The ornamental design for a bottle, as shown.

JOHN A. MAIER.
